UNITED STATES PATENT OFFICE.

THOMAS JOSEPH STURTEVANT, OF WELLESLEY, MASSACHUSETTS, ASSIGNOR TO
STURTEVANT MILL COMPANY, A CORPORATION OF MAINE.

SCREENING OR SEPARATING MACHINE.

1,229,812.

Specification of Letters Patent. Patented June 12, 1917.

Application filed December 12, 1916. Serial No. 136,552.

To all whom it may concern:

Be it known that I, THOMAS J. STURTEVANT, a citizen of the United States, residing at Wellesley, in the county of Norfolk and State of Massachusetts, have invented or discovered certain new and useful Improvements in Screening or Separating Machines, of which the following is a specification, reference being had therein to the accompanying drawings.

This invention relates to separating machines which are made in detachable sections or units placed side by side, so that a machine of any desired capacity may be furnished at short notice, each of the detachable sections or units being provided with its own screens and its own jarring mechanism. This detachable unit construction is advantageous to the manufacturer in that a machine of any desired capacity may be quickly provided by furnishing any desired number of sections or units, and a large machine may be conveniently transported in sections which can be readily secured together in setting up the machine for use. Moreover the user of a machine comprising a number of complete sections or units may set up a machine of any desired capacity by joining together any desired number of such sections or units. In accordance with the present invention a common distributor will supply the material to be screened by the several units or sections of the separating machine, such distributor preferably consisting of a rotary conveyer mounted in a feed box common to the several sections of the screening or separating machine and provided with means for distributing to each section or unit its proper amount of material. This feed box, as also the rotary conveyer or distributor, may be made in detachable sections corresponding to the sections or units of the separator; or the feeding and distributing parts may be made integral, and in such case may be furnished in lengths corresponding to the number of sections or units of the screening or separating machine which are to be used together. The feed box is preferably of such construction that the shaft carrying the rotary conveyer may be readily inserted into or removed from the front thereof, and said feed box is preferably provided with a hinged rear door affording ready access to its chamber, for

adjustment of the feed plate or for other purposes.

In the accompanying drawings Figure 1 is a front view of a two-section or two-unit inclined separator embodying the present invention, with the cover of one section or unit in raised position, and Fig. 2 is a broken out side view of the same. Fig. 3 is an end view of the two-unit separator looking from the bottom of Fig. 1. Fig. 4 is a rear view of the top part of a two-section separator provided with a sectional feed box, and Fig. 5 is an end elevation of one unit of the sectional feed box. Fig. 6 shows in detail a removable front standard or bracing part for the sectional feed box. Figs. 7 and 8 are detail side and end views respectively of one of the removable slides at the ends of the feed box. Fig. 9 is a detail view of part of a sectional conveyer.

Referring to the drawings, 12 denotes the casings of the units of the sectional inclined separator, these casings having complete side parts so that the chambers of the adjoining units or sections are fully divided from each other, each casing thus having its own screening or separating chamber. The sections or units 12 are detachably secured together by means of bolts 10 passing through bracing sleeves 11 interposed between the adjacent sides of the sections or units, as more clearly shown in Fig. 3. Each separator section or unit is provided with a movable cover 13 which is preferably hinged at its top so that it may be lifted, as more clearly shown in Fig. 2, when access to the chamber of a section or unit is desired. The operating portion of the jarring mechanism of each section or unit is mounted on its hinged cover and may be of any desired construction. This operating mechanism, as herein shown, is similar to that shown and described in the Sturtevant U. S. Patents Nos. 1,035,262 and 1,114,064, and comprises rotating shafts 14 mounted on standards fixed to the covers 13, and provided with arms 15 carrying rollers 16 which lift pivoted hammers 17 and which hammers, when released from said rollers, strike on the jarring posts 18. Each screen section is provided with a non-vibrating coarse or scalper screen 19 and a vibrated fine screen 20 below said coarse or scalper screen. The vibrating screen 20 is sustained by spring supports 21 beneath

which are located stops 22 which limit the downward movements of the vibrating screen, these spring supports and stops being preferably located at the sides of the screen, 5 as clearly shown in Fig. 3. The vibrating screens 20 are provided with cross plates 23 on which are mounted sockets 24 which receive the lower ends of the jarring posts 18 passing loosely through sleeves 25 mounted 10 on cross plates 26 with which the scalper screen 19 is provided.

Mounted at the upper ends of the inclined separator sections or units is a feed box 27 in which is journaled a shaft 28 provided 15 with a screw conveyer 29 which distributes the material to be screened or separated and which material is supplied to said feed box from an opening or hopper located at 30 at one end of said feed box at the point where 20 said feed box overhangs the separator, so that the material supplied to the screens will fully cover the same laterally at the upper ends thereof. This feed box and the rotary conveyer or distributor which is 25 mounted therein is common to the several sections or units of the separator so as to supply material to all of the same, such material passing over an adjustable feed plate 31 having an inclined upper edge which is 30 highest at the end of the feed box where the material enters. This feed plate may be made in independent sections, as shown in Fig. 4. The feed box is provided in front with a hinged door or cover 32 which, when 35 unbolted, may be raised for the convenient insertion of the conveyer shaft and its bearings 28^a secured in place by screws or bolts 28^b, and in front of said bearings are slides or removable parts 33 which may be taken 40 out when the conveyer shaft and its bearings are to be removed or inserted, said slides or removable parts being held in place by said door or cover 32 when the latter is closed and secured. The feed box is 45 preferably provided at its rear side with a hinged door 34, affording ready access to the adjustable feed plate 31; and each casing, affording a screening chamber, is also preferably provided at its upper end with a 50 hinged door 35 which may be opened to afford access to said screening chamber, as for the insertion or removal of the screens.

The feed box is preferably removably bolted to the casing sections or units and 55 may be made in one part, as shown in Fig. 1, of a suitable length to supply material to a plurality of screen sections or units; or this feed box may be made in sections, as shown in Figs. 4 and 5, approximately corresponding 60 in length to the width of the sections or units of the screen or separator. In such case the contiguous parts of said screen sections are provided with flanges 36 for the reception of bolts by which said screen sections may be detachably secured together. 65

In order to enable the conveyer shaft to be conveniently removed from or inserted into the front of the feed box in this sectional construction of feed box just referred to, the said feed box will be provided at its front 70 with removable standards or bracing parts 27^a which may be taken out when the hinged door 32 is lifted for the insertion or removal of the conveyer and the feed shaft 28. Also the conveyer shaft and screw conveyer may 75 be made in one part as shown in Fig. 1, or said shaft and its attached conveyer may be made in detachable parts, as shown in Fig. 9, corresponding in length to the width of the detachable casing sections, one part for 80 each section or unit of the screening or separating machine. In this sectional conveyer construction the contiguous ends of the sections of the conveyer are provided with fixed collars 37 having flanges through which attaching screws or bolts 38 pass.

From the foregoing it will be understood that a separator comprising a plurality of detachable sections or units will be provided for supplying the material to be screened or 90 separated to the several sections or units of the separator, and that such common feed box and distributing conveyer, which is removably mounted at the upper ends of the sections or units of the inclined separator, 95 may be made in lengths corresponding to the width of a plurality of separator sections or units, or may be made in detachable parts each corresponding in length to the width of a separator section or unit, these sectional parts being more convenient for transportation than the longer parts would be. 100

The general construction of the sectional separator herein shown and described is not herein claimed, as it forms the subject-matter of my application No. 133,399, filed Nov. 25, 1916.

This invention is not to be understood as being limited to the particular details of construction herein set forth, as such details may be varied widely, within the province of mechanical skill, without departing from the spirit and scope of the invention.

Having thus described my invention I claim and desire to secure by Letters Patent:

1. In a separator, the combination with a plurality of inclined separator sections or units comprising complete casings arranged side by side and detachably secured 120 together and each provided with its own inclined screen or screens and its own jarring mechanism, of a feed box and distributor common to said sections or units, said feed box being removably mounted at the upper 125 ends of said sections or units, and being thus adapted to supply material to all of the same.

2. In a separator, the combination with a plurality of inclined separator sections 130

or units comprising complete casings arranged side by side and detachably secured together and each provided with its own screen or screens and its own jarring mechanism, of a feed box formed in sections corresponding in length to the width of said screen sections or units, and a distributor common to said sections or units, said feed box being removably mounted at the upper ends of said sections or units, and being thus adapted to supply material to all of the same.

3. In a separator, the combination with a plurality of inclined separator sections or units comprising complete casings arranged side by side and detachably secured together and each provided with its own inclined screen or screens and its own jarring mechanism, of a feed box and distributor common to said sections or units and both formed in detachable sections corresponding in length to the width of said separator sections or units, said feed box being removably mounted at the upper ends of said sections or units, and being thus adapted to supply material to all of the same.

4. An inclined separator provided at its upper end with a feed box having a door at its front, a rotary distributor mounted in said feed box, and removable slides at the ends of said feed box in front of said distributor, so that the latter may be inserted or removed from the front of said feed box when said door is opened.

35 5. An inclined separator provided at its upper end with a feed box having a door at its front, a rotary distributor mounted in said feed box and removable slides at the ends of said feed box in front of said distributor, so that the latter may be inserted or removed from the front of said feed box when said door is opened, said slides being held in place in front of the journals of said distributor by said door when the latter is closed.

6. In a separator, the combination with a plurality of inclined separator sections or units comprising complete casings arranged side by side and detachably secured together and each provided with its own

inclined screen or screens and its own jarring mechanism, of a feed box and distributor common to said sections or units, said feed box being removably mounted at the upper ends of said sections or units, and being thus adapted to supply material to all of the same, and said feed box being formed in detachable sections corresponding in length to the width of said separator sections or units.

7. In a separator, the combination with a plurality of inclined separator sections or units comprising complete casings arranged side by side and detachably secured together and each provided with its own inclined screen or screens and its own jarring mechanism, of a feed box and distributor common to said sections or units, said feed box being removably mounted at the upper ends of said sections or units, and being thus adapted to supply material to all of the same, said distributor being formed in detachable sections corresponding in length to the width of said separator sections or units.

8. A separator comprising a plurality of complete separator units detachably secured together and each having its own casing, screens and jarring mechanism, of a feed box mounted at the upper end of said separator units and formed in detachable sections corresponding in length to the width of said separator units, a rotary screw conveyer or distributor mounted in said feed box and formed in detachable sections corresponding in length to the width of said separator sections, and a feed plate formed in independently adjustable sections corresponding in length to the width of said separator sections.

9. An inclined separator provided at its upper end with a feed box having a door at its back, combined with a rotary distributor mounted in said feed box, and a feed plate in said feed box, said feed plate being independently adjustable sections.

In testimony whereof I affix my signature.

THOMAS JOSEPH STURTEVANT.
